UNITED STATES PATENT OFFICE.

COLLINS VAN HOOK, OF KNOXVILLE, TENNESSEE, ASSIGNOR TO UNDERWOOD TYPE-WRITER COMPANY, OF NEW YORK, N. Y., A CORPORATION OF DELAWARE.

TYPE-WRITING MACHINE.

1,299,636.

Specification of Letters Patent. Patented Apr. 8, 1919.

Application filed December 23, 1918. Serial No. 268,594.

To all whom it may concern:

Be it known that I, COLLINS VAN HOOK, a citizen of the United States, residing in Knoxville, in the county of Knox and State of Tennessee, have invented certain new and useful Improvements in Type-Writing Machines, of which the following is a specification.

This invention relates to work-control-
10 ling devices for the revoluble platens of typewriting machines, and is in the nature of an improvement upon the device disclosed in Patent No. 915,875, to McCormack, dated March 23, 1909.

15 In said patent, a label-holding device is placed at one end of the platen, and comprises a feed plate or apron which presses against the platen below the printing line, in addition to rolls which run upon the 20 platen just above the printing line, and which are releasable to permit the withdrawal of the labels. These rolls are carried upon a short arbor or stud, which at one end is mounted or anchored upon an 25 end portion of the platen frame. Since it is important that these parts should be of little weight, they are usually made thin and weak; and, in said patent, a brace is extended forwardly from a platen-frame 30 rod to support said arbor at a point between said rolls.

It is found in practice that not only is it necessary to release the rolls in order to withdraw the typed label, but it may also 35 occasionally happen that a long label will foul said brace arm. It has also been found that if the machine is used for ordinary letter-writing, employing large work-sheets, the width of the sheet is limited by the ne- 40 cessity of avoiding the fouling of said brace arm.

The principal object of my invention is to improve the McCormack machine, so as to make possible the automatic egress of 45 the labels from the machine, and also to render the machine capable of writing upon wider large work-sheets than heretofore, or of writing longer lines upon said work-sheets.

50 In order to attain these ends, in place of the cross-brace or bracing arm 35 seen in said patent, I extend a cross-brace from the same point of engagement with the ar- 55 bor (between the feed rolls thereon) left- wardly past the left-hand feed roll and to-

ward the left-hand end of the platen frame; and then I bend it back and carry it to a point of engagement with the platen-frame rod aforesaid. By the substitution of the new cross-brace arm which extends along 60 the inner roll before reaching back to the rod, it is found that labels can be fed through the machine and emerge therefrom without the necessity of releasing the label-feeding rolls, and also that the entire print- 65 ing field of the platen can be used for the large work-sheets, whereas heretofore a substantial portion of the printing field at the left-hand end of the platen could not be used, on account of the bar which said 70 arm 35 constituted against the egress of the sheets from the machine.

In the accompanying drawings,

Figure 1 is a perspective bottom view of the platen frame of the Underwood type- 75 writing machine provided with the label-feeding rolls, etc., shown in said McCormack patent.

Fig. 2 is a plan of the platen and appurtenances, including my improved cross- 80 brace.

Fig. 3 is a sectional side elevation of the mechanism.

Fig. 4 is a perspective top view showing the improved method of bracing the arbor 85 which carries the roll brackets.

As set forth in said patent, a cylindrical platen 1 is journaled in ends 2 and 3 of a platen frame 4. The platen frame comprises a rod 5 rigidly connecting the ends 90 2, 3, said rod arranged at the rear of the platen 1 and at the upper portion of the platen frame.

The labels may be introduced at the rear of the platen and fed forwardly by the usual bottom rolls 6, 7, and guided up to the printing point by a plate 8; and they may be en- 95 gaged above the printing point by rolls 9, 10, which hold the label or card firmly against the platen, being for this purpose 100 mounted upon inner and outer brackets 11, 12, as set forth in said patent. These brackets are journaled upon a projecting arbor 13, said arbor being anchored only to the left-hand platen frame end 2, this being 105 done by means of a bracket 14 in which the arbor is fixed; said bracket being secured to the platen frame end by a screw 15.

In order to support the right-hand end portion of the arbor in such a manner that the 110

pressure of the rolls 9, 10, upon the sheet or platen shall be about equal, so as to insure even feed of the label or work-piece, I attach to the arbor 13 a supporting boss 16 between 5 the brackets 11, 12, so that the arbor may be supported with sufficient firmness for the purpose. This boss is formed upon a cross-brace 17, which at one end has a boss 18 secured by a set screw 19 to the platen-frame 10 rod 5. The cross-brace 17 comprises a laterally-extending or offset member 20, which extends back of the roll 9, preferably the entire length of the bracket 11, and this bar 20 may be connected by a short, forwardly-extending portion 21 to said boss 16.

It will be seen that a sheet 22, held against the platen by the rolls 9, 10 (Fig. 3), may emerge free from the machine regardless of the cross-brace 17, so that it is no longer necessary to release the rolls 9, 10, (dotted line position at Fig. 3) in order to withdraw the labels. Moreover, the entire printing field of the platen may be employed for wide sheets, since they no longer foul the cross-brace.

Variations may be resorted to within the scope of the invention, and portions of the improvements may be used without others.

Having thus described my invention, I 30 claim:

1. The combination with a revoluble platen and a platen frame, of an arbor fixed at one end upon the end of the platen frame and projecting along the platen, inner and 35 outer brackets journaled upon the projecting portion of said arbor and carrying feed rolls

to run upon the front of the platen, the brackets being rotatable about said arbor to release the rolls from the platen, a fixed rod extending from the end of the platen frame 40 along the platen at the rear thereof, and a cross-brace connecting said arbor to said rod, said cross-brace engaging said arbor at a point between said roll brackets, and extending along the arbor clear of the inner 45 bracket and past the inner roll, and bent to extend back to a point of engagement with said rod.

2. The combination with a revoluble platen and a platen frame, of an arbor fixed 50 at one end upon an end of the platen frame and projecting along the platen, a bracket journaled upon the projecting portion of said arbor and carrying a feed roll to press the work against the platen, the bracket being rotatable about said arbor to release the roll from the platen, a rod fixed to said end of the platen frame and extending along the platen at the rear upper portion thereof, and a cross-brace connecting the projecting portion 55 of said arbor to said fixed rod, said cross brace attached to the arbor at a point beyond said roll bracket, and extending thence along said bracket and past said roll toward the end of the platen frame upon which said arbor is mounted, and there bent to extend rearwardly to a point of attachment to said rod.

COLLINS VAN HOOK.
